(57) **CLAIM**

The ornamental design for a laser shooting gallery, as shown and described.

DESCRIPTION

FIG. 1 is a top, front and left side perspective view of a laser shooting gallery showing our new design;

FIG. 2 is a front elevational view thereof;

FIG. 3 is a left side elevational view thereof, the right side elevational view being a mirror image thereof; and,

FIG. 4 is a top plan view thereof, the bottom plan view being a mirror image thereof.

The broken lines showing of a human figure is for illustrative purpose only and forms no part of the claimed design.
